US00D975448S

(12) United States Design Patent (10) Patent No.: US D975,448 S
(45) Date of Patent: * Jan. 17, 2023

(54) SEALABLE BAG

(71) Applicant: SPACEWHITE PTY LTD, Richmond (AU)

(72) Inventor: Kin Lap Chan, Richmond (AU)

(73) Assignee: SPACEWHITE PTY LTD, Richmond (AU)

() Term: 15 Years

(21) Appl. No.: 29/805,471

(22) Filed: Aug. 27, 2021

(51) LOC (14) Cl. 03-01

(52) U.S. Cl.

USPC D3/303

(57) CLAIM

The ornamental design for a sealable bag, as shown and described.

DESCRIPTION

FIG. 1 is a perspective view of a sealable bag showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the sealable bag that form no part of the claimed design.

1 Claim, 8 Drawing Sheets
